UNITED STATES PATENT OFFICE.

JULIUS MARMOROSKI, OF NEW YORK, N. Y.

DOORLOCK.

Application filed April 28, 1925. Serial No. 26,332.

To all whom it may concern:

Be it known that I, JULIUS MARMOROSKI, a citizen of the United States of America, residing at New York city, Bronx County, 5 and State of New York, have invented certain new and useful Improvements in Door-locks, of which the following is a specification.

This invention relates to locks and to a 10 type particularly adapted for use with automobile doors.

A particular object of the invention is to provide a latch lock which will retain the door closed so that the same can not be 15 evidently opened from within.

A further object of the invention is to provide a lock which can not be opened from inside the car after it has been locked from the outside. That is, in automobiles the 20 window may be lowered and in many cases the lock will be operable from the inside to open the door. My invention prevents any manipulation of the latch after the same has been locked.

25 A further object of the invention is to provide a lock which can be removed without marring or disturbing the upholstery with which the lock is covered, when the lock needs repairing.

30 Referring to the drawing wherein I have shown a preferred embodiment of my invention:—

Figure 1 is a view in elevation of the lock as it would appear from the inside of the 35 door, a portion of which is shown,

Figure 2 is a section through the door immediately above the lock and shows an edge view of the latter,

40 Figure 3 is a view of the lock in side elevation, the cover being removed to show the interior thereof,

Figure 4 is a view in perspective of the lock holder or retainer, and,

45 Figure 5 is a section on the line 5—5 of Fig. 1.

Referring to the drawing in detail 5 indicates a portion of an automobile or like door having a cut out 6 therein to accommodate the lock which consists of a base 7 the 50 forward end 8 of which is obliquely disposed to match the bevel of the door edge 9, the end 8 having screw holes therein through the medium of which the screws 10 may retain the lock base in position. The end 8 55 is also provided with a latch or bolt opening 11 in which is disposed the bolt or latch

12, the same having sliding contact with the base 7 and being maintained in alignment by the boss 13 which projects through an elongated opening 14 in said bolt. The 60 bolt is provided adjacent its forward end with an integral projection 15 which has one face thereof engaged by the finger 16 carried on a collar 17 through a square opening in which, passes the handle operated bar 65 18. This finger 16 is of course operated by the handle 19 on the outside of the door, and in turn slides the bolt back into the lock to release the door in the usual manner, the bolt itself being normally retained in its 70 extended position by the spring 20 which engages the rear face of the projection 15, before referred to. The rear end of the bolt is provided with a cut-out 21 and an extended cam portion 22, the finger 23 of a 75 handle operated collar 24 extending into said cut-out 21 to render the bolt locked or unlocked. The extension 25 on the collar 24 is cut on its edge to provide two seat portions 44 and 45 which may alternately engage a protuberant portion formed in a spring 26 which is attached to the lock base 7. The extended part 25 when the handle 27 is revolved engages the cam portion 22 80 to operate the bolt. Therefore, a movement in one direction of the handle will operate the bolt or latch. The end of the finger 23 may be turned to engage cut-out 21 so that the bolt or latch 12 can not have free rearward movement when the door is closed. The 85 latch is cammed back by its passage over the keeper plate shown in the outline as at 28, the latch itself being rounded as at 29 on one side to allow of its riding over said keeper plate, when the finger 23 is not engaged in cut out 21.

The upper or top edge of the bolt is provided with a notch 30 one side of which is obliquely disposed and in this notch engages the hooked end 31 of a lever 32 pivoted to base 7 as by the rivet 33, the other end of the lever being provided with a pin engaging end 34 which is engaged by the free end of a pin 35 which is carried in a lock barrel, the lock being preferably of the tumbler type and key operated, so that when the lock is revolved to locking position, the hook is engaging the notch in the bolt, and the latter will be fixed in position and the door securely locked. A revolving movement of the pin 35 either raises or lowers the hooked end of the lever 32.

It is necessary that some means be provided in automobile doors for placing a lock which can be removed for repair without marring the upholstery and I provide a retainer 36 of channel formation and substantially U-shape and having in its ends the ears 37, the same having openings therein through which pass the screws 38 to hold the retainer in place in the opening 6 of the door. The side of the retainer at one end is provided with similar openings for the accommodation of screws 39. In this portion I also provide an inwardly bent integral piece 40 in which are cut the slots 41. These slots are adapted to frictionally receive the projections 42 formed on the end of the base 7, so that the lock base and its cover 43 when all assembled as one complete unit may be slid into the retainer 36 and held securely therein without being otherwise held through the medium of long screws which are objectionable inasmuch as they become loose and the lock rattles and mars the inside of the door. By removing the screws 10 in my construction the whole lock may be drawn out of the door, for repair or cleaning without damage to the upholstery.

It will be evident therefore that I have provided a lock of novel construction and also a novel means of holding the same securely in position in the door. Further, the construction of the lock is such that the inside handle may have a play or free movement so that accidental turning of the same will not open the door. Further the whole may be covered with upholstery in any desired manner and thereby concealed and

no removal of the upholstery is necessary when the lock itself is removed.

Having described my invention, what I claim is:

1. A lock member comprising a base plate, a bolt slidable thereon and having an opening and cut outs therein, finger members disposed in said cut outs, one of said finger members being adapted to move the bolt longitudinally, and the other of said finger members being adapted to prevent longitudinal movement of the bolt, and means in said opening for guiding the movements of said bolt.

2. A lock member comprising a bolt, having projections thereon, one of which serves as a cam, operating members adapted to engage said projections to move the bolt longitudinally, and the cam engaging operating member having an extended finger which lies within one of said cut outs, whereby when said member is operated said finger will move the bolt longitudinally.

3. A lock comprising a casing, a bolt slidable in said casing and having an opening therein, a guide member extending into said opening, projections on the lower edge of said bolt, operating members for engaging said projections whereby the bolt may be cammed to a position inside the casing, a notch in the top edge of said bolt, and a pivoted locking lever adapted to engage said notch to prevent withdrawal of the bolt.

In testimony whereof I hereunto affix my signature.

JULIUS MARMOROSKI.
